UNITED STATES PATENT OFFICE.

EDWARD J. BODEY, OF CINCINNATI, OHIO, ASSIGNOR TO THE ECLIPSE FOLDING MACHINE COMPANY, OF SIDNEY, OHIO, A CORPORATION OF OHIO.

SUCTION-CLEANER.

1,104,613.

Specification of Letters Patent.

Patented July 21, 1914.

Application filed September 24, 1913. Serial No. 791,549.

To all whom it may concern:

Be it known that I, EDWARD J. BODEY, a citizen of the United States, residing at Cincinnati, in the county of Hamilton and State of Ohio, have invented certain new and useful Improvements in Suction-Cleaners, of which the following is a specification.

My invention relates to portable suction cleaners, and is exemplified as a suction cleaner having a plurality of suction-openings, in one of which a brush is located.

The invention consists in novel means for adjusting and rotating the brush; in novel means for supporting the suction cleaner upon the surface to be cleaned, in novel means for adjusting the height of its suction-opening with which the brush coöperates with relation to said surface, and the invention will be further readily understood from the following description and claims, and from the drawings, in which latter:

Figure 1 is a side elevation of my improved device showing its handle in ordinary working position in full lines and in assumed position in dotted lines. Fig. 2 is a plan view of the same, with the handle in ordinary working position and partly broken away. Fig. 3 is a vertical section on the line 3—3 of Fig. 2, showing the driving means for the brush. Fig. 4 is an enlarged detail of the same, shown on the same section. Fig. 5 is a rear perspective view of the adjustable wheel support located at the left side of the machine. Fig. 6 is a central vertical section of my improved device taken on the line 6—6 of Fig. 2. Fig. 7 is a vertical cross-section, taken on the line 7—7 of Fig. 2. Fig. 8 is a vertical cross-section taken on the line 8—8 of Fig. 2, showing the lips of the suction-opening with which the brush coöperates and the brush in low position, induced by the adjustment of the adjustable wheels; and, Fig. 9 is a similar view, showing the lips of the suction-opening with which the brush coöperates and the brush in a raised position.

I have illustrated my improved device as of the general form as that shown and described in my application for Letters Patent on suction cleaners, filed November 11, 1912, Serial No. 730,663, and the present invention is intended as an improvement on the suction cleaner shown and described and claimed in my aforesaid application.

11 represents the case of my improved device in which a fan 12 rotates, the fan being secured to the lower end of an armature shaft 13 of an electric motor 14 mounted on the case. The case has an exit-port 15 communicating with a suitable bag 16 serving as a dust separating device. The bag has support from a handle 17 by means of a spring 18.

21 is a nozzle releasably secured to the case as by means of set-screws 22. The nozzle has a suction chamber 23 therein which communicates with the chamber 24 in the case through a passage 25. The nozzle in the present exemplification forms a releasable base for the case.

I prefer to provide the nozzle with a lateral extension 27 at each corner thereof. Suction-openings 28, 29, are formed in the nozzle and extend lengthwise of said lateral extensions. The suction-openings are located side by side in spaced apart relation and are preferably of comparatively different widths, the narrow suction-opening 28 being located at the rear and the wide suction-opening 29 being located at the front of the device.

The mouth of the suction-opening 28 has an outer lip 31 and an inner lip 32, and the mouth of the suction-opening 29 has an outer lip 33 and an inner lip 34. One of the lips of each of said suction-openings, when the suction-nozzle is in operating relation with the surface 35 to be cleaned, is higher than the other of said lips, instanced in this case as the inner lips 32, 34, which are shown higher than the outer lips 31, 33, whereby inlet-spaces 36, 37, into the chamber 23 through said respective openings are insured. The said chamber has a bottom 38 which connects the adjacent lips 32, 34, of the suction-openings of the nozzle, and is shown of arch-form for forming a substantial draft-space 39 under the suction cleaner leading to the inlet-spaces 36, 37.

I prefer to provide a brush, shown at 41, in the wider of said suction-openings and to rotate said brush, so that its contacting part with the surface being cleaned moves in a direction opposite to the movement of the suction cleaner over said surface, and further to provide means whereby the lips of the suction-opening in which the brush is located may be raised or lowered with re-

lation to the surface being cleaned; and, I have further preferred to provide means whereby said brush may also be raised and lowered with relation to said surface, but preferably to different extent from the raising and lowering of the said lips, and to provide means whereby the brush may readily be removed from the device.

I provide the adjustment stated to accommodate different surfaces to be cleaned, for instance, if a polished floor or other unyielding surface is to be cleaned it is advisable to have the lips of the suction-opening and the brush in close proximity to said surface, whereas, for instance, in cleaning carpets having a long nap, it is desirable to raise said lips of the suction-opening and the brush with relation to the supporting wheels adjacent thereto, for the reason that the wheel or wheels sink into the nap, the adjustment preventing too close proximity of the lips of the suction-opening to the nap, thereby avoiding closing of the suction-openings by the nap and insuring proper passage of the air and dirt to be removed through the suction-opening.

45, 45, are a pair of supporting wheels located in substantial line with and at the ends of the suction-opening 29. Each of these wheels rotates on an axle 46 rigid with a plate 47 pivoted on a screw 48 screwed into the end wall 49 of the suction-opening 29 and arranged to swing on said pivot for raising or lowering the wheel with relation to the suction-nozzle. Each of the plates is positioned by means of a set-screw 50 threaded in a threaded hole 51 in a lug 52 extending from the plate 47 and selectively received in one of the notches 53 of the nozzle. The lugs 52 on the plates 47, at opposite ends of the nozzle, as shown in Fig. 2, extend inwardly in opposite directions.

The brush 41 comprises a shaft 55, the ends whereof rotate in bearings formed by slots in the plates 47 and the ends of suction-opening 29. The wheels are shown of housing form and each incases a gear 57 rotating therewith, the gears 57 meshing with pinions 58 at the respective ends of the brush-shaft. The shaft of the brush passes through a slot 59 at each end of the nozzle and through a slot 60 in each of the plates 47. The slots 59 and 60 at the respective ends of the nozzle cross each other and are arranged so that substantial meshing of the gears 57 and pinions 58 is maintained throughout the adjustments of the plates, and so that the wheels are adjusted greater distances than the brush when said plates 60 are adjusted.

The slots 59 are shown as upright slots, whereas the slots 60 are slots which extend preferably in a curve transverse to the slots 59 and open inwardly from the peripheries 65 of the plates 47, the parts being preferably

so arranged that greater comparative up and down movements are imparted to the wheels than to the brush by the swinging of the plates 47. This has the advantage that when the wheels are in up-position, 70 positioned for cleaning an unyielding surface, as shown in Fig. 8, the lips of the suction-opening are closely adjacent to the surface being cleaned, and the surface contacting portion of the brush contacts said surface. When the wheels are in down-position, 75 as shown in Fig. 9, positioned for cleaning a long-nap carpet, into which the wheels sink, the lips of the suction-opening are raised for insuring proper passage 80 through the inlet-spaces 36, 37, above the nap of the carpet, the brush being raised to comparatively less extent for insuring proper brushing of the nap, and avoiding excess of friction therewith.

The axes of the wheels, brush and the pivots of the plates are preferably triangularly arranged, as will be noted in Figs 7, 8 and 9, the axes being arranged in parallel vertical planes, the vertical plane in which the axes of the pivots is located being spaced from the vertical planes in which the axes of the brush and wheel are located. The distance between the axes of the wheel and pivot is preferably greater than the distance 90 between the axes of the brush and pivot.

The teeth of the gear 57 and of the pinion 58 are preferably sufficiently long to maintain meshing relation between the same throughout the range of adjustment of the 100 wheels, the gear 57 in its adjustment moving about the pinion to a certain extent to aid in maintaining the meshing of their teeth.

The suction cleaner is shown supported on the wheels 45 at the front end thereof 105 and on a wheel 61 at the rear thereof, the wheel 61 being mounted on a stud 62 in brackets 63 extending from the nozzle, the wheels as shown forming a three-point support for the device.

The set-screws 50 may be withdrawn sufficiently for permitting sufficient swing of the plates 47 for permitting removal of the brush through the outer ends of the slots 59, 60.

The handle 17 is at its lower end provided with a fork 66, the tines of which are pivoted on screws 67. One of the tines is provided with an arc-slot 68 through which a clamp-bolt 69 extends into the case for clamping the handle in selective adjusted positions. The greater portion of the arc-slot 68 is at one side of a right line drawn between the pivot 67 and the outer end of the handle for permitting the handle to be 110 arranged to be swung into suitable angles with relation to the vertical, or to be placed in a substantially vertical position so as to be out of the way and to cause the device to 115 take up little floor space.

Having thus fully described my invention, what I claim as new and desire to secure by Letters Patent, is:

1. In a portable suction cleaner, the combination of a suction-nozzle, a supporting wheel therefor, a plate on which said wheel rotates pivoted to said nozzle, a brush, said nozzle and plate having crossing slots by the walls whereof said brush is positioned, and means for positioning said plate with relation to said nozzle for adjusting the height of said nozzle and of said brush with relation to said wheel.
2. In a portable suction cleaner, the combination of a suction-nozzle, a supporting wheel therefor, a plate on which said wheel rotates pivoted to said nozzle, a brush, said nozzle and plate having crossing slots by the walls whereof said brush is positioned, the axes of said wheel, brush and pivot being triangularly arranged, the vertical plane in which the axis of said pivot is located being spaced from the vertical planes in which the axes of said wheel and brush are located, and means for positioning said plate with relation to said nozzle.
3. In a portable suction cleaner, the combination of a suction-nozzle, a supporting wheel therefor, a plate on which said wheel rotates pivoted to said nozzle, a brush, said nozzle and plate having crossing slots by the walls whereof said brush is positioned, the axes of said wheel, brush and pivot being triangularly arranged, the distance between said axes of said wheel and pivot being greater than the distance between the axes of said brush and pivot, the axes of said wheel and pivot being in different vertical planes and means for positioning said plate with relation to said nozzle.

4. In a portable suction cleaner, the combination of a nozzle, a supporting wheel therefor, a plate on which said wheel rotates, said plate pivoted to said nozzle, a gear rigid with said wheel, a brush, a pinion on said brush meshing with said gear, said nozzle and plate having crossing slots in which said brush is mounted.

5. In a portable suction cleaner, the combination of a nozzle, a plate, a brush, a wheel journaled to said plate, said plate pivoted to said nozzle, said nozzle and plate provided with coacting crossing slots the walls whereof position said brush, driving means between said wheel and brush for rotating said brush, the relations of the walls of said slots and of the axes of said wheel, brush and pivot being such that when said plate is swung downwardly said brush is moved downwardly to less extent than the downward movement of said wheel.

6. In a portable suction cleaner, the combination of a suction-nozzle having a suction-opening, a brush therein, a roller-support pivoted to said suction-nozzle, a roller thereon for supporting said nozzle said roller-support and nozzle having crossing slots extending inwardly from the peripheries of said roller-support and nozzle respectively, said brush being received through said slots and positioned by the walls thereof and releasable from said walls by the swinging of said plate.

In testimony whereof, I have hereunto signed my name in the presence of two subscribing witnesses.

EDWARD J. BODEY.
